UNITED STATES PATENT OFFICE.

FREDERICK GARGIULO, OF NEW HAVEN, CONNECTICUT.

RADIATOR UNIT.

Application filed April 20, 1921. Serial No. 463,023.

This invention relates to radiators and more particularly radiators for cooling the engines of automotive vehicles and is especially concerned with elongated radiator units comprising one or more tubes which are adapted for use in the construction of such radiators. While the invention may be found particularly useful in connection with radiators of this type, the principles thereof are not limited to such radiators, however, but may be used in connection with others.

Heretofore it has been common to provide tubular radiator units consisting of separate tubes of appropriate material, such as brass, copper, or other suitable metal, each tube having a plurality of fins or flanges suitably secured to the exterior surface of the tube as by soldering. The fins are spaced from each other at appropriate intervals and usually formed in the shape of a flat disk or plate which projects laterally from the tube, the parts of the fin lying in a single plane, the purpose being to increase the effective radiating surface of the tube and thereby increase the cooling effect.

With such an arrangement it is seen that the air in passing through the radiator and cooling the fluid therein will pass directly from the front to the back of the radiator without having absorbed as much heat from the fluid within the radiator as is possible. It is, therefore, proposed to construct a radiator such that the air will not be allowed to pass directly through the same, but will be deflected transversely of the direction of this passage and its turbulence will be so increased by the formation of transverse waves that when it finally emerges it will have absorbed practically all of the heat from the fluid within the radiator that it is capable of absorbing.

One object of my invention is, therefore, to provide a new and improved radiator wherein transverse waves will be set up in the air or cooling fluid passing therethrough so that the turbulence thereof will be increased to render the radiator much more efficient.

Another object of my invention is to provide a new and improved tubular unit for radiators which shall consist of a plurality of tubes (two or more) which have their walls formed of a single piece of sheet metal which will be common to the tubes of one unit. It is thus seen that one wall of each of the tubes of this unit will be integral with one wall of the adjacent tube of the unit.

A still further object of my invention is to

provide a new and improved fin surrounding the tubes of one of the radiator units.

Further my invention consists in the provision of a tubular radiator unit which shall consist of a plurality of tubes having at least some of their walls in common, that is, formed from the same piece of material, such tubes being placed substantially in a row and surrounded by a fin of such character that it will deflect the currents of air striking the same to the adjacent fin above or below the one under consideration, where it will in turn be reflected to the first fin so that the existence of cold cores in the air passing through the radiator will be eliminated or substantially reduced.

The fin structure which I provide to increase the radiating surface of the fluid carrying tubes may consist either of individual fins, each of which is provided with an opening to receive the tubes, or a continuous plate extending transversely across the radiator and provided with a plurality of openings, each of which is adapted to receive one of the tubular units.

To these and other ends the invention consists in the novel features and combinations of parts to be hereinafter described and claimed.

In the accompanying drawings:

Fig. 1 is a front elevational view of an engine cooling radiator embodying my improvements;

Fig. 2 is a detail elevational view of a portion of the same, some parts being shown in section;

Fig. 3 is a sectional view along line 3—3 of Fig. 2;

Fig. 4 is a top plan view of one of the tubular radiator units;

Fig. 5 is a sectional view on line 5—5 of Fig. 3;

Fig. 6 is a sectional view on line 6—6 of Fig. 4;

Fig. 7 is a top plan view of a tubular radiator unit showing a somewhat modified construction;

Fig. 8 is a detail elevational view similar to Fig. 2, but showing a modified construction in which the fin structure is shown as a continuous plate extending transversely of the radiator and the tube structure is shown as one elongated tube extending from front to rear of the radiator;

Fig. 9 is a plan sectional view on line 9—9 of Fig. 8;

Fig. 10 is a view similar to Fig. 9 showing a modified construction in which the tube structure extending from front to rear of the radiator consists of a plurality of separate tubes.

I have selected for illustration an engine cooling radiator particularly adapted for use on automotive vehicles, for example, motor trucks driven by internal combustion engines, in which case the water for cooling the engines circulates in a generally vertical direction between the upper and lower tanks or headers, as customary, through vertical tubes connecting the tanks, the cooling effect being produced by the passage of air between the tubes in a generally horizontal direction. It will be understood, however, that the invention is applicable to other uses and that it is not restricted to cases where the fluid to be cooled consists of water passing through the tubes and the cooling fluid consists of atmospheric air, nor to cases where interchange of heat is effected between fluids of these two kinds.

In the drawing, the tubular radiator units 10 are shown as set in between and connected with upper and lower water tanks or headers 11 and 12 respectively. These tanks are shown as connected by the side spacing members 13 and 14.

The upper tank 11 is more fully shown in Fig. 2 where it is shown as bolted to a header plate 15, which forms the lower base of the tank 11, and is provided with a plurality of openings or perforations 16 for the insertion of the tubes which provide the communication between the upper and lower tanks.

The invention is particularly concerned with construction of the tubular units connecting the two tanks and the fins which are provided thereon to increase the radiation therefrom. As clearly shown in Figs. 4 and 6, each tubular unit 10 is formed of a plurality of tubes 17 which are disposed in substantial alignment from front to back of the radiator, although this disposition may be varied, if desired. Three of these tubes are shown as constituting one of the units 10, although the exact number used is not important and may, of course, be varied as desired.

As shown, the units consist of two spaced walls 18 and 19, which are connected at their ends to close the tubes at the ends of the series. As shown in Fig. 4, it may be found desirable to form these two walls 18 and 19 of a single sheet of metal, which will be turned or bent back upon itself at an intermediate portion to form one end 20 of the series of tubes, while the other ends are lapped, as shown at 21, and soldered to form a watertight joint at the other end of the series. If a separate sheet of metal is used for each of the walls 18 and 19, they would, of course, have their edges lapped and soldered at both ends of the tubular unit.

In any event the wall 18 will consist of a single piece of material which will extend along and form a common wall for a plurality of the tubes.

To form the partitions between the adjacent tubes of a series, grooves are provided in the walls 18 and 19, which form convex shoulders 22 upon the opposite side of said walls, which shoulders project toward each other and meet when the two walls are assembled, thus forming partitions between the adjacent tubes and serving to space the walls 18 and 19 the required distance apart. The meeting edges of the shoulders 22 are soldered so as to form a watertight joint between the adjacent tubes. 75 80

Fins 23, as shown in Fig. 3, are provided with an elongated opening and placed upon the tubular unit above described, so that the row of tubes is received within the opening provided and the fins are then soldered in place. The fins are provided with small flanges 24 which assist in connecting the fins rigidly to the tubes and also increase the conducting surface between the fin and tubes. 85 The fins 23 are of peculiar construction, as best shown perhaps in Figs. 3 and 5. The front portion of the fin is inclined to the horizontal so as to slightly deflect the air which passes through the radiator. This portion of the fin is inclined upwardly, as shown in Fig. 95 3, to the point denoted by the letter *a*. From that point to a point intermediate the length of the fin denoted by the letter *b* it is inclined slightly downwardly from the horizontal. The rear half of the fin is then symmetrically 100 formed with the front half just described being inclined upwardly from the point denoted by the letter *b* to that denoted by the letter *c* and then inclined downwardly from that point to the end of the fin. The intermediate 105 portion of the fin between the points *a* and *c* forms a trough, the edges of which, lying beyond these points, are downwardly inclined.

As will be obvious from an inspection of the drawing, when the air strikes the front portion of any one of the fins, the particles of air which lie above the fin will be deflected toward the lower downwardly inclined surface of the fin just above the one under consideration, while the particles of air which lie below the fin will strike the downwardly inclined surface thereof. It will be seen, therefore, that the passage of air through the radiator in a straight line is, to some extent, prevented and, moreover, the currents of air are so deflected that they strike the surface of the fins at an inclination and are thereby effectively spread out so that a greater exchange of heat is brought about 115 than were the currents of air to strike these fins when moving generally perpendicularly to the surface thereof. When the air strikes the downwardly inclined surface of a fin between the points *a* and *b*, it will be deflected to 120 125 130

the upwardly inclined surface of the fin below between the points *b* and *c*. It will then pass to the downwardly inclined surface between the point *c* and the rear end of the fin. It will be obvious that a very effective cooling and exchange of heat between the fluid passing through the tubes and the fluid passing between the fins will be brought about. The fins are also provided with corrugations 25 extending around the same, as shown in Fig. 4, which will serve to increase the disturbance in the air passing through the radiator and also serve to strengthen the same.

As shown in Fig. 4, when each tubular unit 15 is formed of one sheet of material, so that only one soldered joint 21 is required, this is placed at the back of the radiator where it will be conveniently accessible in case repairs are needed. Moreover, this is a decided advantage in the construction shown in Fig. 4 20 where the tubes of one of the units have a common wall such as the walls 18 or 19, so that the joints will occur at the front or back only. If the two walls are formed separately, 25 there will, of course, be a joint at both front and back walls.

In Fig. 7 I have shown a modified construction wherein the tubes 17' comprising the unit 10 are formed separately, and in this 30 case the fin 27 is provided with three openings or one for each of the separate tubes 17' instead of one elongated opening to receive all of the tubes, as in the form shown in Figs. 1 to 6. The fins 27 used in connection with 35 this unit are of the same type as that just described in connection with the other figures of the drawings and will act in the same way when in use.

In the construction of the form of my device shown in Figs. 1 to 6, a piece of sheet metal of appropriate size may be provided with the grooves required to form the shoulders 22 at the necessary places and then bent upon itself to form the two parallel walls 18 and 19, the ends overlapping, as shown in Fig. 4, and the shoulders 22 meeting to form the partitions between the tubes. The fins may then be slipped upon the unit thus formed and the whole dipped into a bath of 50 solder to secure the fins to the tubes and to make watertight the lap joints at the rear ends of the tubes. The exact order in which the steps are carried out, however, to construct my improved radiator is not important, and, of course, may be varied as found desirable.

In Figs. 8 and 9 I have shown a further modification in which the tube structure 17^b is shown as one elongated tube extending 60 substantially from front to rear of the radiator, these tubes being surrounded by a fin structure 23^b which is a continuous plate extending transversely of the radiator to embrace a plurality of the tubes. The fin structure is of the improved form shown in Figs.

2 and 3, except that instead of consisting of fins which are separately formed, a plate is provided which is formed in cross-section like the separately formed fins of Fig. 3 to extend across the radiator and embrace a 70 plurality of the tube structures. It may be here stated that the term "tube structure", as used in this application, denotes the fluid carrying passages and may refer to a tube structure consisting of separate passages or 75 ducts, as shown in Figs. 4 and 7, or to one elongated tube, such as shown in Fig. 9. In like manner the term "fin structure" is used broadly to refer either to separate fins individual to a tube surrounded thereby, as 80 shown in Fig. 2 or to a fin structure in the form of a plate embracing a plurality of tube structures, such as is shown in Fig. 9.

In Fig. 10 I have shown in plan view a portion of a radiator in which the tubular units are composed of separately formed tubes 17', as shown in Fig. 7, surrounded by a fin structure which consists of a continuous plate 27^a similar to the plate 23^b shown in connection with the elongated tube in Fig. 9. This plate 27^a will, as previously described, be similar in cross-section to the fins 23 shown in Figs. 1 to 6. In case a continuous plate is employed, bent to provide deflecting portions, as shown and described in 95 connection with Figs. 8, 9 and 10, the shallow corrugations in the plate shown in the drawings as surrounding the respective tube structures, may be omitted if desired, the main feature in this case being the shaping of the 100 plate in such a manner by bending or otherwise as to cause the deflection of air in the manner previously described. It is, of course, obvious that the particular tube structure shown in Fig. 4 may be provided with 105 the continuous plate of Fig. 9, with or without the surrounding corrugations.

While I have shown and described with particularity some preferred forms of my invention, it is understood that the same is not to be limited thereto in all of its details, but is capable of any modifications and variations which lie within the spirit of the invention and within the scope of the appended claims.

What I claim is:

1. A fin for tubular radiators, comprising an elongated body provided with an opening adapted to receive a tubular structure having a plurality of aligned parallel fluid channels, said elongated body having portions adjacent its front and rear edges turned at a slight angle to the horizontal, and an intermediate V-shaped portion adapted to extend beyond the tubular structure at the front and rear of an intermediate fluid channel and to overlap the front and rear fluid channels and to extend outwardly away from said tubular structure at each side thereof.

2. In a radiator for a motor driven vehicle

130

wherein a cooling fluid is caused to rapidly pass therethrough, a radiator core comprising a plurality of spaced apart series of vertically disposed water channels, the water channels of each series being in alignment from the front to the rear of said core, the water channels of each series having a plurality of spaced apart horizontally disposed fin structures associated therewith, said fin structures extending from beyond the front water channel to beyond the rear water channel and at the sides thereof, said fin structures

being inclined upwardly forwardly of the front water channel, inclined downwardly and then upwardly intermediate the front and rear water channels, and inclined downwardly rearwardly of the rear water channels, whereby the rapidly passing cooling fluid will be deflected in a wavy path while passing through said core. 15

In witness whereof, I have hereunto set my hand this 18th day of April, 1921. 20

FREDERICK GARGIULO.
